UNITED STATES PATENT OFFICE

NORMAN W. CUMMINS, OF LOUISVILLE, KENTUCKY

DESIGN FOR A CUP

Application filed July 14, 1932. Serial No. 44,323. Term of patent 7 years.

To all whom it may concern:

Be it known that I, NORMAN W. CUMMINS, a citizen of the United States, residing at Louisville, in the county of Jefferson and State of Kentucky, have invented a new, original, and ornamental Design for a Cup, of which the following is a specification, reference being had to the accompanying drawing, forming part thereof.

Figure 1 is a side elevational view, Fig. 2 is a top view, Fig. 3 is a bottom view.

I claim:

The ornamental design for a cup as shown.

NORMAN W. CUMMINS.
